DESIGN FOR A TEXTILE FABRIC

Mary F. Faulconer, New York, N. Y.

Application January 12, 1942, Serial No. 105,160

Term of patent 3½ years

To all whom it may concern:

Be it known that I, Mary F. Faulconer, a citizen of the United States, residing in New York city, in the county of New York and State of New York, have invented a new, original, and ornamental Design for a Textile Fabric, of which the following is a specification, reference being had to the accompanying drawing, forming part thereof.

The figure is a plan view of a piece of textile

fabric showing my new design, a unit of which is contained between the dot-and-dash lines, the same being repeated in regular succession as indicated by the extensions beyond the unit boundaries.

I claim.

The ornamental design for a textile fabric, substantially as shown and described.

MARY F. FAULCONER.
